UNITED STATES PATENT OFFICE.

ESTELLE C. RANEY, OF COLUMBUS, OHIO, ASSIGNOR TO THE AUTOMATIC RECLOSED CIRCUIT BREAKER COMPANY, OF COLUMBUS, OHIO, A CORPORATION OF OHIO.

AUTOMATICALLY-RECLOSED CIRCUIT-BREAKER MECHANISM.

1,302,851.

Specification of Letters Patent. Patented May 6, 1919.

Application filed October 12, 1915. Serial No. 55,415.

To all whom it may concern:

Be it known that I, ESTELLE C. RANEY, a citizen of the United States of America, residing at Columbus, in the county of Franklin and State of Ohio, have invented certain new and useful Improvements in Automatically-Reclosing Circuit-Breaker Mechanism, of which the following is a specification.

My invention relates to automatically reclosing circuit breakers. In the application of such breakers to feeders of a load circuit which is supplied by current at more than one point, such as a feeder to a trolley line which is supplied by current from two or 15 more stations, there are two distinct conditions under each of which the automatic reclosing circuit breaker must function properly.

First: When the breaker opens due to a local overload which does not cause all the breakers in the other feeders to open. In this case a potential will exist on the load side of the open breaker. This potential may vary in value from a few volts up to 20 normal value. Under this condition the reclosure of the breaker must be governed in accordance with this potential to prevent the reclosure of the breaker until the overload has been removed to a safe value.

Second: When the breakers on all feeders to a common load circuit are opened by a short circuit, or when all stations except one are shut down, the reclosing of the breaker must be governed in accordance with the 25 value of the load resistance in such a manner that the breaker will not reclose until the short circuit has been removed or the load resistance increased to a safe limit.

It is the purpose of the present invention 40 to provide a circuit breaker which will automatically adapt itself to operate properly under either of the conditions cited above.

The preferred embodiment of my invention is shown in the accompanying drawings 45 wherein similar characters of reference designate corresponding parts and wherein the paths of currents are indicated under the different conditions by the heavier lines.

Figure 1 is a diagrammatic representation 50 of two substations feeding a load circuit, the reclosing circuit breaker mechanism being diagrammatically shown.

Fig. 2 is a simplified diagram of the essen-

tial elements of the apparatus shown in Fig. 1, all the breakers being closed.

Fig. 3 is a diagram showing one of the breakers open and the other closed.

Fig. 4 is a diagram showing all of the breakers open.

In the drawings the two feeder circuits 60 may be designated "A" and "B". The load circuit comprises the wires 1 and 2. The feed wires of station A are designated 3 and 4 while feeder wires of station B are designated 5 and 6. At station A and at station 65 B are located automatically reclosing circuit breakers which are identical in structure. Therefore, description of one of these circuit breakers will be sufficient to clearly demonstrate the nature of both.

Each breaker has a main contact member 7 movable into closed position by a pivoted lever 8 which is under the control of core 9 of a lifting coil 10. The plunger 9 of the lifting coil 10 carries a lateral extension 75 adapted when raised to lift and thereby open a dashpot switch 11 which would otherwise bridge contacts 12 and 13.

The circuit of coil 10 is designed to be 80 opened to permit the contact member 7 to drop open upon overload or short circuit by a switch member 15 through the medium of an overload coil 14. When this switch 15 is opened it is automatically grasped and held open by a latch 16.

Reclosure of the breaker must be effected 85 by closing the circuit of the lifting coil 10. This is accomplished by the trip coil 17 which is operable under certain prescribed conditions to trip the latch 16 and thus release the switch 15.

The circuit of trip coil 17 is under the control of coil 37 and a compound coil 31-29 which automatically adapt the circuits of my apparatus to either the first 95 or second condition named above as such conditions exist or arise. The manner in which this is effected may best be described in the operation which follows.

The operation of my device may be best 100 set forth with reference to Figs. 2, 3 and 4 of the drawings.

In Fig. 2, with special reference to station A, the main contact bridge is closed and will be maintained in the closed position in normal operation by the action of a

pivoted arm 8 which is actuated by an extension 9 of the core of solenoid 10. Elevation of this core will also serve to raise the dashpot switch 11, which switch in closed position connects points 12 and 13.

In normal operation the solenoid 10 is energized by current from generator through wire 49, series coil 14, wire 45, resistance 46, contact 47, contact arm 15, wire 48, coil 10 to wire 3, completing the circuit to the generator.

In case of an excessive flow of current through series coil 14 of the circuit breaker, the core of coil 14 will be raised and operate 15 on extension of contact 15 causing its rotation out of contact with point 47. This action deenergizes coil 10, resulting in the opening of the circuit breaker in which the parts assume the position shown in Fig. 3.

20 It will be noted that at the instant contact arm 15 is opened by the core of overload coil 14 a latch 16 engages arm 15 in such a manner as to hold arm 15 out of contact with point 47. The reclosure of the 25 circuit breaker can now be effected only by the operation of coil 17 on latch 16 to release contact 15 so that it will then engage contact point 47.

Fig. 3 illustrates conditions of operation 30 when the circuit breaker at station A has opened and when one or more other feeders are still supplying current to the load circuits 1 and 2.

Fig. 4 illustrates conditions of operation 35 when all of the circuit breakers have opened.

The operation of coil 17 is governed by three different elements. First, the dashpot bridge 11 maintains the circuit of coil 17 open at points 12 and 13 for a definite 40 time interval after the circuit breakers open. After circuit has been completed at points 12 and 13 there are two coils, namely, coil 37 and compound coil 31-29, either of which coils may control the completion of 45 circuit of coil 17. Assuming the breaker at station A to have opened due to overload while the breaker at station B still remains closed, as shown in Fig. 3, causing the energization of load wires 1 and 2, coil 31 will 50 be energized through wire 4, wire 30, coil 31 and wire 32.

The core of coil 31 is so constructed that a low potential between wires 1 and 2 will 55 energize it sufficiently to maintain contact bridges 26 and 22 open between points 27-25 and 23-21 respectively. Thus, when there is more than a few volts potential on the line after one breaker has opened, these 60 bridges are maintained in the open or raised position. Under this condition the energization of coil 17 is governed by the operation of coil 37 on core 38 to connect points 35 and 36 by means of bridge 39. With the breaker in the open position and the double 65 bridge member raised, as shown in Fig. 3,

coil 37 is subjected to the full potential of load circuits 1 and 2 as follows: From wire 2, through wire 4, through wire 30, through coil 37, through wire 40 to contact points 13 and 12 to wire 3.

70 Coil 37 is preferably designed so that it may be set to operate on any desired line potential between 50% of normal value and full potential. It is obvious that it would be undesirable for a breaker to reclose so long as an overload existed opposite such breaker which would cause its immediate opening, if it were to close. The desirable load potential for the operation of coil 37 will be governed by local conditions and it is 75 therefore desirable that the coil 37 be readily adjustable for any desired point of operation.

At the instant the potential between wires 80 1 and 2 increases to the point for which the operation of coil 37 is adjusted, bridge 39 will close contact points 35 and 36. A current will then flow from generator A through wire 50 to resistance 18, wire 34, contact bridge 39, wire 24, wire 41, through 85 coil 17, contact points 13 and 12 to wire 3. This current will energize coil 17 to release latch 16 which in turn allows contact arm 15 to complete the circuit of coil 10, resulting in the reclosure of the circuit breaker. The reclosure of the breaker opens the circuit between points 13 and 12 and all parts 90 resume the position shown in Fig. 2.

The second condition of the operation of the trip coil 17 is illustrated diagrammatically in Fig. 4 in which case all feeder breakers to the load circuit wires 1 and 2 have been opened with the result that relay coil 31 is deenergized allowing contact bridges 26 and 22 to close the circuit between points 25-27 and 21-23. With the circuit thus established, a limited current is shunted around the open breaker from generator A through wire 50, resistance 18, wire 42 to point 19 from whence two parallel circuits to wire 3 are established. One circuit is from point 19 through contact 25-27, wire 28, low resistance winding 29, to wire 30, to wire 4, to wire 2, thence through load or short circuit to wire 1 and 100 through wire 1 to wire 3 returning to generator station A. The other circuit from point 19 is through bridge member 22, wire 41, coil 17, through bridge 11 to wire 3. So long as the short circuit exists at point c, Fig. 4, or a load of extremely low resistance 105 is connected between wires 1 and 2, the greater part of current through resistance 18 will be shunted through the load circuit, by way of bridge 26, wire 28, coil 29, wire 30, wire 4, wire 2, short circuit c to wire 1, to wire 3. However, with an increase of load 110 resistance between wires 2 and 1, a greater portion of the current will be diverted to the other circuit, through bridge 22, wire 115 120 125 130 135 140

41, coil 17, bridge 11 to wire 3. When the resistance has reached a sufficiently high value, enough current will flow through the last named circuit to operate coil 17 and release latch 16 with the result of closing the circuit breaker.

From the description, it will be apparent that I have provided a circuit breaker which will open in case of an overload or short circuit, and which will reclose automatically whenever the potential of load circuit is high enough to preclude an excessive flow of current from the feeder whose breaker is open, or whenever the load resistance is of sufficiently high value to prevent an excessive flow of current.

Having thus described my invention, what I claim is:

1. A circuit breaker comprising means for opening the circuit breaker on overload, means for reclosing the circuit breaker, and means operative when there is more than a definite minimum potential in the load circuit to govern operation of said reclosing means by potential of the load circuit and operative when there is less than said minimum potential to govern operation of said reclosing means in accordance with load resistance.

2. A circuit breaker comprising means for opening the circuit breaker on overload, means for reclosing the circuit breaker, means operative when there is more than a definite minimum potential in the load circuit to govern operation of said reclosing means by potential of the load circuit and preclude reclosing until a definite higher potential is exceeded, and means operative when there is less than said minimum po-

tential to govern operation of said reclosing means in accordance with load resistance.

3. A circuit breaker comprising means for opening the circuit breaker on overload, means for reclosing the circuit breaker, means operative by substantially normal potential of the load circuit to connect said reclosing means to the source of supply, and means operative to connect said reclosing means to the source of supply only after the potential of the load circuit has dropped below a predetermined minimum.

4. A circuit breaker comprising means for opening the circuit breaker on overload, means for reclosing the circuit breaker, means operative by substantially normal potential of the load circuit to connect said reclosing means to the source of supply, and means operative to connect said reclosing means to the source of supply only after the potential of the load circuit has dropped below a predetermined minimum, said means being disconnected whenever the potential of the load circuit rises to substantially normal value.

5. A circuit breaker comprising means for opening the circuit breaker on overload, means for reclosing the circuit breaker, means for causing actuation of the reclosing means above a predetermined high voltage point, by which connections said reclosing means are actuated above a predetermined low voltage point, and means operative to complete said connections only when said voltage has dropped below a predetermined voltage.

In testimony whereof I, hereby affix my signature.

ESTELLE C. RANEY.
